UNITED STATES PATENT OFFICE.

ADOLF SCHILLER, OF BERLIN, GERMANY.

PRESERVE JAR AND THE LIKE.

Application filed August 28, 1926, Serial No. 132,303, and in Germany August 29, 1925.

This invention relates to the air tight closing of vessels, more particularly of those used as preserve or jam jars, in which it is usual to provide a flanged face surrounding the 5 mouth of the vessel, on which face is placed a flat elastic ring with which the lid or cover makes a tight joint.

In order to insure a reliable tight joint, it is necessary, in the usual constructions, to grind 10 both the face of the vessel on which the packing ring is placed and the face of the lid which engages with the packing ring, as the unevenness of the surfaces occurring in the normal manufacture is too great to enable 15 a reliable joint to be insured without subsequent treatment. Moreover, in the usual vessel and lid constructions, the ground faces utilized for the joint are very liable to be damaged, more particularly when the vessel 20 is being opened.

According to the present invention the disadvantages in question are eliminated by retaining the flat rubber ring placed on an annular face of the vessel and by effecting the 25 tight joint between the vessel and the lid by means of a face of the lid which is slightly tapered. It has been found that by utilizing more particularly the outer edge of the flat rubber ring, an excellent joint is obtained, 30 without it being necessary to grind even one of the two faces which engage from the opposite sides with the rubber ring.

More particularly good results are obtained when the slightly tapered pressure face of the 35 lid projects beyond the outer edge of the packing ring and terminates in a downward flange which forms an efficient protection for the packing face and may be used as a grip for opening the lid if the vessel be suitably 40 constructed.

An embodiment of a preserve jar with the closing device according to this invention is illustrated in the accompanying drawing.

The jar is marked 1 and the lid 2. 3 is the 45 bearing face surrounding the opening of the vessel and intended for the flat rubber ring 4. 5 is the pressure face of the lid which engages from the top with the rubber ring 4 and terminates in a downward flange 6. The face 50 5 as shown in the drawing has a slightly tapering shape, so that it first engages only with the outer edge of the ring 4. When the lid is tightened and there is a vacuum in the interior of the jar, the edge portion of the 55 ring is preferably compressed. 7 is a projecting portion of the vessel which is so arranged

below the ring bearing face 3 of the jar that when the lid is put on the rubber ring, the flange 6 of the lid is situated above the portion 7 of the vessel and at a certain distance 60 from the same.

It will be seen that flange 6 extends below the rubber ring 4 and the faces 3 and 5 of the jar and lid, respectively, which contact with said ring. The flange 6 thus protects 65 these faces 3 and 5 and the rubber ring from damage, such as might be occasioned by the insertion of opening tools.

The opening of the vessel may be effected in a simple manner by introducing a tool substantially radially to the vessel between the projecting portion 7 of the vessel and the flange 6 of the lid, and by using it as a lever swinging the outer lever arm upwardly. This requires the provision of bearing surfaces for 70 the tool one at the inner end of the projecting portion 7 of the vessel and the other at the outer edge of downward flange 6 in substantially lateral displacement with relation to each other so that on upward swinging of 75 a tool radially disposed to the jar the inner end of same presses the jar downwardly and the middle portion bearing against the free edge of downward flange 6 pushes the lid upwardly. Even on forcefully pushing the lid 80 upwardly no tilting effect is exercised on the jar and no damaging effect neither on the surfaces of the jar and of the lid bearing against surfaces of the rubber ring nor on the rubber ring itself. 85

In place of the annular flanges or projecting portions 6 and 7 may be provided also single projections, in which case, of course care must be taken to see that when the lid is 90 put on, they are exactly above one another. 95

The projecting portions of the jar and the lid forming the slot for introducing an opening tool should be so shaped that the surfaces forming the slot are either both substantially perpendicular to the axis of the jar or that the 100 surface of the jar is perpendicular to the axis and that of the cover inclined in conformity with the wall of an upright cone so that the tool can be firmly positioned with its point on the surface of the jar and that a good 105 opening leverage is secured.

What I claim is:—

The combination with a jar made of glass or the like having a flat annular surface on its outside near its mouth and a flat annular 110 resilient gasket contacting with said surface, of a cover made of glass or the like having a

slightly inclined inner annular surface opposed to said flat outer surface of the jar, the two opposed annular surfaces adapted to effect compression of said gasket increasing 5 from inside to outside of the gasket, the cover being provided with a flange projecting downward from the outer edge of said slight-

ly inclined inner annular surface, the vessel provided with a second annular surface opposed to and spaced from the lower face of 10 said downwardly projecting flange of the cover.

In witness whereof I affix my signature.
ADOLF SCHILLER.
